GENERAL MERCHANDISING MACHINE CABINET

Walter L. Koch, Livingston, N.J., assignor to Rowe Manufacturing Company, Inc., New York, N.Y., a corporation of New York

Application January 8, 1959, Serial No. 54,090

Term of patent 14 years

(Cl. D52—3)

Figure 1 is a perspective view of a general merchandising machine cabinet showing my new design. The rear portion of the cabinet not visible in the drawing is plain.

I claim:

The ornamental design for a general merchandising machine cabinet, substantially as shown and described.
